G. P. McDONNELL

FIRE EXTINGUISHER

Filed Oct. 1, 1919

Patented Mar. 11, 1924.

1,486,531

UNITED STATES PATENT OFFICE.

GEORGE P. McDONNELL, OF ST. LOUIS, MISSOURI.

FIRE EXTINGUISHER.

Application filed October 1, 1919. Serial No. 327,647.

To all whom it may concern:

Be it known that I, GEORGE P. McDONNELL, a citizen of the United States of America, a resident of the city of St. Louis, 5 in the State of Missouri, have invented certain new and useful Improvements in Fire Extinguishers, of which the following is a full, clear, and exact description, reference being had to the accompanying drawings, 10 forming a part of this specification.

My invention relates to improvements in fire extinguishers, one of the objects being to produce a simple and effective automatic fire extinguisher. Another object is to produce 15 a portable fire extinguisher adapted to be controlled by hand and also adapted to be operated automatically.

Prior to this invention, it has been customary to equip buildings with portable fire extinguishers, which are to be manipulated by hand in the event of a fire. The best known type of these portable extinguishers consists of a chemical mixing tank containing pressure producing chemicals which 20 mingle with each other when the tank is inverted, and the tank is usually provided with a flexible discharge tube having a nozzle at its free end. An important object of my invention is to enable a portable fire extinguisher of this kind to automatically discharge its contents in response to the heat resulting from a fire. I accomplish this 25 by means of a simple combination of elements, which allow the extinguisher to be quickly removed from its support and manipulated by hand in the usual manner. The particular combination of elements herein shown can be easily attached to an ordinary 30 portable fire extinguisher, at a very low cost.

With the foregoing and other objects in view, the invention comprises the novel construction, combination and arrangement of parts hereinafter more specifically described 45 and illustrated in the accompanying drawings wherein is shown the preferred embodiment of the invention; however, it is to be understood that the invention comprehends changes, variations and modifications which 50 come within the scope of the claims hereunto appended.

Fig. I is a side elevation illustrating a fire extinguisher embodying the features of this invention, a portion of the chemical-mixing 55 receptacle being broken away to show the acid bottle.

Fig. II is a fragmentary view, showing the clip whereby the discharge tube is held within the lower end of the chemical-mixing receptacle.

Fig. III is a horizontal section through the upper portion of the receptacle, illustrating the fusible band.

A designates a chemical-mixing receptacle adapted to contain the usual solution of bicarbonate of soda, and B designates a bottle arranged in the upper portion of said receptacle and adapted to contain an acid. When the receptacle is inverted, the acid will escape from the bottle and commingle 70 with the solution to form a gas under pressure, as is well understood in the art. The usual flexible discharge tube 1 extends downwardly from the upper end of the receptacle A. A nozzle 2, secured to the lower end of tube 1, lies adjacent to the lower end of the receptacle. It will be observed that the elements just described constitute a well-known portable fire extinguisher. Without materially affecting the portability of the extinguisher, I provide it with a few simple attachments and thereby convert it into a combined portable and automatic fire extinguisher.

3 designates a contractile band surrounding the receptacle A in a horizontal plane below the center of gravity of the receptacle. The ends of the band 3 are connected by a bolt 4 (Fig. I), which may be adjusted to firmly secure the band to the receptacle. 75 Studs 5, extending from the band 3, are provided with nuts 6 whereby plates 7 are loosely secured to the studs. Flexible suspension chains 8, located at opposite sides of the receptacle A, are secured at their lower 80 ends to the plates 7, and the upper ends of these suspension chains are provided with hooks 9 adapted to be detachably secured to a supporting bracket 10, as shown in Fig. I. Obviously, these hooks can be easily and 85 quickly removed from the bracket to permit the device to be operated in the usual manner as a portable fire extinguisher.

To retain the suspended fire extinguisher in an upright position, a fusible band preferably surrounds the receptacle A and chains 8 in a plane above the center of gravity of the receptacle. This fusible band may consist of a fibrous cord 11 and a fusible link 12 connecting the ends of said cord. Heat 110 insulating material 12' is interposed between the link 12 and the receptacle. The link may

be fused by the heat resulting from a fire, and the cord 11 will burn when exposed to the flames. This fusible band, located near the top of the receptacle, retains the lower portions of the suspension chains in proximity to the receptacle, while the upper portions of the chains diverge from the upper end of the receptacle. When the fusible band is released the receptacle will drop a slight distance, causing the chains 8 to occupy the positions shown by dotted lines, and the receptacle will then be freely suspended from the studs 5, which lie below the center of gravity. As a consequence, the suspended receptacle will quickly tilt, or turn on the studs 5, to the inverted position shown by dotted lines in Fig. I. When this occurs, the acid flowing from the bottle B will commingle with the solution in the receptacle, with the result of forcibly discharging the mixture through the discharge tube 1.

When the extinguisher is operated automatically, as just pointed out, it is usually desirable to discharge the fire extinguishing fluid onto the ceiling of the room, so as to distribute the fluid over a large area. The nozzle 2, at the lower end of the flexible discharge tube, is therefore directed away from the top of the receptacle and secured in this position by means of a double spring clip C. As shown by Figs. I and II, the spring clip comprises clip members embracing the nozzle and clip members embracing the lower edge of the receptacle. By securing the nozzle in this manner, it can be quickly detached when the extinguisher is to be operated by hand. When operated automatically, the receptacle is suspended in an inverted position, and the secured nozzle will then direct the outgoing stream onto the ceiling. The pressure resulting from this stream will cause the freely suspended receptacle to swing in an irregular manner, so as to distribute the fire extinguishing fluid over a very large area.

An electrical fire alarm is shown at the top of Fig. I, and this alarm is controlled by the fire extinguisher. The alarm may consist of an electric bell 13 connected to a battery 14, and the bell circuit may include a movable armature 15 and a stationary contact 16 adapted to cooperate with said armature to complete the circuit. 17 designates a spring tending to pull the armature into engagement with the contact 16. An electromagnet 18 normally holds the armature 15 in the position shown in the drawing. When the magnet is de-energized, the spring 17 will pull the armature 15 onto the contact 16, so as to close the alarm circuit. The magnet circuit includes a battery 19 and con-

ductors connected to binding posts 20 on a switch housing 21. A controlling switch, located in this housing, includes a fixed contact 22 connected to one of the binding posts 20, and a movable contact arm 23 connected to the other binding post. The movable contact arm 23 is pivoted at 24, and it may be separated from the fixed contact 22 to open the magnet circuit, thereby releasing the armature 15 to close the bell circuit. A weighted arm 25, extending from the contact arm 23, rests upon the circular handle 26 at the top of the receptacle. When the fire extinguisher is removed from the supporting bracket 10, or when it is automatically inverted, the weighted arm 25 will drop by gravity, so as to open the controlling switch and thereby sound the alarm.

I claim:

1. An automatic fire extinguisher comprising a chemical-mixing receptacle, a plurality of flexible suspension means secured to said receptacle whereby said receptacle is tiltably supported, a fusible means encircling said flexible suspension means above the center of gravity of said receptacle and retaining portions of said flexible means against the body of said receptacle, said flexible suspension means diverging upwardly from said receptacle above the encircling fusible means, and a support to which the divergent flexible means is secured, whereby said receptacle is permitted to drop relatively to said support and be inverted when said fusible means is broken.

2. An automatic fire extinguisher comprising a chemical mixing receptacle provided with a flexible discharge tube and a nozzle at the discharge end of said tube, said nozzle being directed downwardly from the lower portion of said receptacle, means for securing said discharge tube near the lower end of said receptacle, flexible suspension members arranged at opposite sides of said receptacle and having their lower ends secured to said receptacle below the center of gravity thereof, a support above said receptacle to which said flexible suspension members are secured, and a fusible band embracing said receptacle and suspension members in a plane above the center of gravity of the receptacle, whereby said receptacle is held in an upright position and permitted to be inverted when said fusible band is broken, so as to permit free and irregular flexure of said flexible suspension members while the fluid is discharged upwardly from the nozzle.

In testimony that I claim the foregoing I hereunto affix my signature.

GEORGE P. McDONNELL.
